UNITED STATES PATENT OFFICE.

IRVING I. FRANKEL, OF CINCINNATI, OHIO.

COAT COLLAR AND METHOD OF PRODUCING AND APPLYING THE SAME.

Application filed July 25, 1925. Serial No. 46,158.

To all whom it may concern:

Be it known that I, IRVING I. FRANKEL, a citizen of the United States, residing at Cincinnati, in the county of Hamilton and 5 State of Ohio, have invented a new and useful Coat Collar and Method of Producing and Applying the Same, of which the following is a specification.

The present invention is a coat collar and 10 the method of making and applying the same.

Heretofore it has been the common practice in the making of coats (when basting the collar thereon), to gather the lower edge 15 of the "stand" portion of the collar at points over the shoulders (or at the shoulder seams), in order to produce a fullness between these or other prescribed points, enabling the collar to set up close to the neck 20 or shirt collar, and at the same time emphasizing the lines of the collar and lapel. This operation when the basting is done either by hand or by machine requires great skill 25 and care in properly tailored coats and, therefore, forms one of the most important 30 and costly operations in coat construction.

The object of the present invention, therefore, is, first, to replace by relatively inexpensive non-skilled labor an operation now 35 done mostly by hand and (when done either entirely by hand or partly by machine) requiring highly skilled workmanship and operators and, second, to insure the execution of this important operation in coat construction with a greater degree of accuracy and a large saving of time, all resulting in a reduction in the production cost.

With these and other objects in view, the invention broadly contemplates performing the above described gathering operation 40 prior to the attaching of the collar to the coat, whereby the collar may be applied by a mere stitching or sewing without requiring skilled labor for this particular operation.

In this specification and the annexed drawings, the invention is disclosed in the form in which it is considered to be the best, but the invention is not limited to such 45 form and method because it is capable of being embodied in other forms and being performed in a different manner; and it is to be understood that by and in the claims 50 following the description herein, it is intended to cover the invention it may embody 55 within the scope thereof.

In the drawings which show the preferred embodiment of the invention as at present employed:

Fig. 1 is a front view of a coat illustrating the inner collar of the invention, and with portions broken away over one shoulder to illustrate the relative position of the parts when assembled;

Fig. 2 illustrates an inner collar as ordinarily used in coat construction and in its flat form;

Fig. 3 illustrates a portion of the collar illustrated in Fig. 2 folded on the line $x-x$ of Fig. 2 to provide the stand portion of the 70 collar which is gathered at its lower edge in accordance with the invention;

Fig. 4 is a top plan view of the collar as shown in Fig. 3;

Fig. 5 is a front view similar to Fig. 3 75 showing the collar including the gathered portion pressed, and

Fig. 6 is a top view of the collar as illustrated in Fig. 5.

Referring in detail to the drawings 10 illustrating a coat collar of the usual construction foldable on a line substantially represented by $x-x$ on Fig. 2 which is usually provided by a suitable line of stitching, known as the "break," thereby forming the 80 inner or stand portion of the collar 11 and the outer or leaf portion 12. The collar, as shown in the drawings, is what is generally termed the inner collar, that is, the lining A and stiffening material B without the facing or covering cloth of the suiting, which latter is commonly known as the "outer collar."

The stand portion of the collar, preferably at its lower edge and adjacent the ends 95 thereof, or at such other points as lie about or over the shoulder of the wearer, are gathered, as indicated in Fig. 3, by any suitable means to provide a fullness c in the stand portion at this point which causes 100 the convexed contour as indicated at c' , causing the folded edge or break portion of the collar to be raised as indicated at c'' to conform to the contour of the neck and to lie closely thereagainst or against the 105 shirt collar. In the present showing, this gathering is produced on a machine known as a "gatherer" which gathering is maintained in position by a line of stitching also made by the machine, although any other 110 means may be employed for producing the gathering and for maintaining it, or for

otherwise providing such fullness at the points mentioned on the collar. For instance adhesive may be used or pins, staples and other fastening means, for holding the gathering.

When the collar as shown in Figs. 3 and 4 has been provided, it is ready to be applied to the neck opening of the coat 13 in the usual manner by stitching 14, which may be effected either by hand or by machine and without the necessary skill now required to effect the gathering or "fulling in" of the collar at the time the collar is being applied, thus saving considerable time in the operations necessary for the application of the collar to the coat and in the labor costs thereon. Of course, it is to be understood that the collar 10 shown in the drawings is to be covered by an outer collar 20 of suitable material, such as the cloth of the suiting, or on overcoats it may be of velvet.

Obviously the method employed in practicing the present invention includes, first, the provision of the inner collar in the usual way, then gathering or fulling in the edge of the stand portion of the collar to provide a fullness, at points thereon which overlie the shoulder, previously to the application of the collar to the coat; then applying the collar to the coat by stitching the same directly to the coat in any suitable manner, and then finishing the coat and the collar thereof as usual.

Having thus described the invention and in which manner the same shall be performed, what I claim is:

1. The method of applying collars to coats which consists in gathering the stand portion of the collar transversely of its length at spaced points in its length and maintaining said gathering therein prior to the application of the collar to the coat, and then securing the stand portion of the collar to the coat in the usual manner.

2. The method of applying collars to coats which consists in gathering the stand portion of the collar along its lower edge portion and on opposite sides of the back portion of the collar to produce a bulging fullness in said stand portion and maintaining said gathering therein, then applying the collar to the coat by an ordinary stitching operation.

3. As a new article of manufacture, a coat collar having a collar-engaging stand portion, and a leaf portion, and means on said stand portion producing a bulg-

ing fullness prior to the application of the collar to the coat, said fullness being at points therein to substantially overlie the shoulders of the wearer.

4. As a new article of manufacture, an inner coat collar having stand and leaf portions, said stand portion being gathered for a distance along the length of the collar, and means for maintaining said gathering in the collar prior to the application of a collar to the coat, said stand portion being adapted to be secured to a coat.

5. As a new article of manufacture, a coat collar having stand and leaf portions, said stand portion being gathered for a distance along the length of the collar at points substantially overlying the shoulders of the wearer, when in applied position on the coat, and means for maintaining said gathering in the collar prior to its attachment to a coat, the collar thus constructed being attachable to a coat during the construction of the latter.

6. As a new article of manufacture, a coat collar having a collar-engaging stand portion said stand portion being gathered substantially transversely for a distance at spaced points in its length, and a line of stitching maintaining said gathering therein prior to the attachment of the collar to the coat.

7. As a new article of manufacture, an inner coat collar having a collar-engaging stand portion, said stand portion being gathered for a distance along its lower edge at spaced points in its length and a line of stitching maintaining said gathering therein prior to the attachment of the collar to the coat.

8. A coat collar having a coat-engaging stand portion and a leaf portion, said stand portion having permanently maintained transversely arranged gathers at spaced positions in its length, whereby a fullness in the collar is produced prior to its attachment to a coat.

9. The combination with a coat of a collar having a stand portion and a leaf portion, stitching connecting the stand portion with the coat, and means independent of said stitching for maintaining transversely arranged gathers at spaced positions in the length of said stand portion, whereby a fullness in the collar is produced.

In testimony whereof I have hereunto set my hand.

IRVING I. FRANKEL.
